(57) **CLAIM**

The ornamental design for a urinal seal, as shown and described.

DESCRIPTION

FIG. 1 is a rear perspective view of a urinal seal;
FIG. 2 is a side view thereof;
FIG. 3 is a top view thereof;
FIG. 4 is a bottom view thereof;
FIG. 5 is a cross section view along Line 5-5 as shown in FIG. 2 thereof.
FIG. 6 is a rear perspective view of a urinal seal;
FIG. 7 is a side view thereof;
FIG. 8 is a top view thereof;
FIG. 9 is a bottom view thereof;
FIG. 10 is a cross section view along Line 10-10 as shown in FIG. 7 thereof;
FIG. 11 is a rear perspective view of a urinal seal;
FIG. 12 is a side view thereof;
FIG. 13 is a top view thereof;
FIG. 14 is a rear view thereof;
FIG. 15 is a cross section view along Line 15-15 as shown in FIG. 12 thereof;
FIG. 16 is a rear perspective of a urinal seal;
FIG. 17 is a side view thereof;
FIG. 18 is a top view thereof;
FIG. 19 is a rear view thereof; and,
FIG. 20 is a cross section view along Line 20-20 as shown in FIG. 17 thereof.
